FISHER COMPANY, OF HARRISBURG, PENNSYLVANIA, A CORPORATION OF
DELAWARE.

TYPE-HEAD SHIFTING AND LOCKING MECHANISM.

1,119,149.

Specification of Letters Patent.

Patented Dec. 1, 1914.

Application filed February 6, 1911. Serial No. 606,935.

To all whom it may concern:

Be it known that I, HARRY A. FOOTHORAP, a citizen of the United States of America, residing at Harrisburg, in the county of Dauphin and State of Pennsylvania, have invented certain new and useful Improvements in Type-Head Shifting and Locking Mechanism, of which the following is a specification.

10 My present invention relates to typewriting machines, and more particularly to that class of such machines which are characterized by what are known as plural type heads mounted on the type bars and designed to be automatically shifted to present either an upper or lower case character in the printing position.

15 The primary object of the invention is to provide an improved mounting for the head and improved means for locking the head in normal or lower case position and for releasing the head and shifting the same to upper case position during the printing operation.

20 To this end the invention contemplates the equipment of each type bar with a shiftable plural type head, a locking member which retains the head rigidly in normal position, and a head releasing and shifting device which when brought into contact with a relatively fixed part or tripper during the printing stroke of the bar will move the locking element to release the head and shift the released head to the upper case position.

25 In the accompanying drawings—Figure 1 is a sectional view of so much of a typewriting machine as is necessary to properly disclose a type bar equipped in accordance with my invention, several positions of the bar being indicated in dotted lines. Fig. 2 is a side elevation on a somewhat enlarged scale of the type bar disposed in normal position and indicating in dotted lines the positions assumed by the bar and head when the bar carrying a shifted head has nearly reached its fully retracted position. Fig. 3 is a similar view showing the relation of the parts when the head shifting device or trigger comes into contact with the trip during the stroke of the type bar. Fig. 4 is a side view showing the relation of parts when the bar has progressed sufficiently beyond the position shown in Fig. 3 to cause the arrest-

ed trigger to release the head preparatory to the shifting thereof. Fig. 5 is still another view of this character showing the positions assumed by the parts when the bar has progressed sufficiently to cause complete shifting of the head from upper to lower case position, the position assumed by the trigger or head shifting device under the impulse of the spring after said device has cleared the trip being indicated in dotted lines. Fig. 6 is a detail sectional view showing the mounting of the head at the upper end of the type arm. Fig. 7 is a perspective view of the upper end of the type bar showing the head, the head locking spring, and the combined head shifting and releasing device in normal position, and Fig. 8 is a detail view of the trip and its operating key.

30 Fig. 1 indicates the frame of a typewriter mounted to travel over the flat platen 2 and equipped with downwardly acting printing mechanism having the form of swinging type bars 3 suitably mounted in bearings 4 in the carriage 5. The type bars are operated by keys 6 carried by key levers 7 fulcrumed as for instance at 8 and having depending arms 9 connected by draw wires 10 and 11 and sublevers 12 with the type bars. Above the bearings 4 is mounted a backing or buffer 13 which limits the backward or retractile movement of the type bars under the impulse of retracting springs 14 connected at their upper ends to the buffer and at their lower ends to the type bars.

35 At the upper end of each type bar 3 is mounted what is known as a plural type head 15 carrying upper and lower case type 16 and 17, the latter or lower case type being normally disposed in the printing position, as shown in Fig. 2. The head 15 is mounted to rotate on a headed stud 18 having a reduced portion 19 passed through and rigidly secured in the upper end of the bar 3. The upper end of the bar 3 is cut away or halved on one side to accommodate the head which thus lies flush with one side of the bar and has a curved bearing face 20 opposed to a bearing face or shoulder 21 of similar curvature formed by the halving of the bar. The side face of the type head is countersunk to accommodate the head 18a of the stud 18 and attention is directed to the fact that the head is afforded bearings on both the stud 18 and head 18a which consti-

tute journals of comparatively great diameter and serve, in conjunction with the bearing faces 20 and 21, to insure an absolute effective mounting for the head.

- 5 At opposite ends of the bearing face 20, which is of course concentric with the axis of the head, said head is formed with a pair of stop faces 22 and 23 which engage opposite edges of the type bar and limit the rotary movement of the head in opposite directions. In other words, the shoulders 22 and 23 limit the movement of the head to an oscillation sufficient to present either of the types 16 or 17 in the printing position.
- 10 15 In rear of its axis the type head 15 is provided with a bifurcated tail 24 having a locking face 25 approximately radial with respect to the axis of the head and designed to coact with a locking member 26 carried by the arm 3 and serving to lock the head in normal position. The locking member 26 may be and preferably is in the form of a flat spring having its upper end bowed back from the bar 3 and provided with an angular end 27 normally lying under and in obstructing relation to the locking face 25 of the tail. The locking member or spring 26 extends along the rear edge of the bar 3 and has its lower end bent at an angle to form 25 a retaining lug 28 engaging a notch 29 cut in the rear edge of the bar. Intermediate of its ends the spring 26 is formed with integral clips 30 and 31 which embrace the bar and securely but detachably retain the 30 35 spring 26 thereon.
- Pivotedly mounted in the bifurcated tail 24 as by a pintle 32 is what I term the combined head releasing and shifting device 33. This device is in the form of a flat metal plate provided in rear of its pivot with a releasing cam 34, below its pivot with a stop lug 35 and above the axis of the type bar with a tripping arm or trigger 36. The front edge of the arm 36 is normally disposed radially with respect to the axis of the type head and at its inner end normally abuts against the bottom wall of the tail bifurcation, as indicated at 37, which also coacts with the stop 35 after limited movement of the device 33 on its own axis. The releasing cam 34 of the shifting and releasing device 33 normally lies above the locking face 25 of the tail 24, but when the releasing member 33 is swung relative to the type head, said cam coacts with the upper end of the locking spring 26 and moves the latter rearwardly out of engagement with the locking face 25 of the tail 24. When this disengagement has been effected, the rear end of the cam 34 will be opposed to the vertically disposed portion of the spring 35 and the stop 35 will engage the abutment 37 to prevent further independent rearward movement of the device 33. The head releasing and shifting device 33 and the head

will now be connected and become in effect a single structure which will swing to shift the head from lower to upper case position, where the head is arrested by the engagement of the stop face 20 at the rear side of the type bar. 70

The foregoing description will be fully understood by reference to Figs. 2, 3, 4 and 5 of the drawings. For convenience of description the movement has been considered as though the bar 3 were standing still and the device 33 swung rearwardly to first release and then shift the head. So far as the relative movements and positions of the type bar and the parts carried thereby are concerned, this assumption is entirely correct, but as a matter of fact, the initial swinging of the member 33 to release the head and the subsequent shifting of the head is effected not by the rearward swinging of the member 33, but by the arresting of said member temporarily during the downward movement of the type bar. For instance, in the full lines of Fig. 2 the normal position of the type bar and head are shown. After 80 the type bar has progressed for something less than one-half of its stroke, the arm or trigger 36 of the device 33 comes into contact with a relatively fixed trip 38 which has been depressed by the manipulation of a shift key 39 and intermediate connections 40 into obstructing relation to the trigger. As the bar continues its downward movement, as shown in Fig. 4, the temporary arrest or retardation of the trigger 33 will 90 cause that relative movement of the releasing cam 34 and locking member 26 which is necessary before the shifting of the type head on the bar can commence. The head being released from the locking member, and the trigger having reached the limit of its movement relative to the head, the continued downward movement of the bar and the continued retardation of the trigger will cause the head to be shifted from lower case to 100 upper case position, as indicated in Fig. 5, and when the trigger has cleared the trip 38 it will be thrown back, as indicated in dotted lines in Fig. 5, to its normal position relative to the head. In this shifted position of the head, however, the trigger 36, instead of extending in line with the bar as it does in normal position, will be disposed at an obtuse angle with respect to the bar and will project rearwardly. When the bar 110 returns, after having effected the printing of an upper case character, the trip 38 will have been elevated out of the path of the trigger and the head will therefore stay in its shifted or upper case position until just 120 before the bar reaches the position of rest. The upper end of the trigger or head shifting device will engage the buffer 13. As further rearward movement of the upper end of the trigger is now prevented by the 130

buffer 13, the final portion of the retractile movement of the bar will effect the reshifting of the type head 15 to normal position, upon reaching which the locking member 5 26 will snap under the locking face 25 of the head and automatically lock the same in its normal or lower case position.

Attention is now directed to the fact that the spring 26 not only constitutes a locking member for the head, but that it also insures the complete shifting of the head, since it will be evident that as soon as the tail piece 34 of the head moves below the upper end of the spring 26, the latter will 10 exert pressure on said tail piece in a plane below the axis of the head, the spring pressure being sufficiently great to swing the head and thus complete the shifting movement thereof in the event that the trip 38 15 is released and allowed to rise out of coaction with the arm 36 of the head shifting device 33 before the head has been completely shifted.

It is thought that from the foregoing, the 25 construction and operation of the type head and head shifting and locking mechanism constituting my invention will be clearly understood, but I wish to reserve the right to effect such modifications of the illustrated 30 structure as may come fairly within the scope of the protection prayed.

What I claim is:—

1. The combination with a type bar and a plural type head thereon, of a locking member coacting with the head, and a head releasing and shifting device carried by the head and coacting with the locking member.
2. The combination with a type bar and a plural type head shiftably mounted on the 40 bar, of a locking member carried by the bar and engaging the head to lock the same in one position, and a head releasing and shifting device pivotally mounted on the head and coacting with the locking member.
3. The combination with a type bar, of a plural type head pivotally mounted at the outer end thereof and having a tail piece, a locking member carried by the type bar and movable into and out of engagement with 50 the tail piece of the head, and a head shifting and locking device pivotally mounted on the head and having a releasing cam movable to shift the locking member to its releasing position.
4. The combination with a type bar and a type head pivotally mounted at the outer

end thereof, of a locking spring carried by the type bar and engaging the head, and a head releasing and shifting device mounted on the head and having limited movement 60 relative to the head to effect the release of the same from the locking spring.

5. The combination with a plural type head, of a locking spring engaging the head and locking the same against movement in 65 the direction of its shift and operative to complete the shifting of the head, and means for releasing the head from the locking spring and for imparting initial movement to the head to bring the head and spring in 70 such coactive relation as will enable the spring to complete the shifting movement.

6. The combination with a type bar, of a plural type head pivotally mounted thereon and having stops coacting with the bar to 75 limit the movement of the head and also having a tail piece extended rearwardly from said head, and a locking spring carried by the bar and engaging the tail piece of the head, and a combined head shifting 80 and locking device pivoted on the tail piece, said shifting and locking device having a releasing cam coacting with the locking spring, an arm extending beyond the head for coaction with a trip, and stop portions 85 which coact with the head to limit the independent movement of the releasing and shifting device thereon.

7. The combination with a plural type head, of a locking member engaging the 90 head to positively retain the same against movement in one direction, and a releasing device movably mounted on the head and operative to move the locking member to release the head, the releasing device and head 95 being movable together to shift the head after the release of the latter.

8. The combination with a type bar having its upper end halved and formed with two arcuate bearing surfaces, of a headed 100 stud carried by the halved portion of the bar, and a plural type head journaled on the stud and having internal and external arcuate bearing faces opposed to the respective bearing faces of the bar.

In testimony whereof I affix my signature in presence of two witnesses.

HARRY A. FOOTHORAP.
